W. H. SAUVAGE

REGULATOR FOR BRAKE RIGGING

Filed March 22, 1927

UNITED STATES PATENT OFFICE.

WILLIAM H. SAUVAGE, OF NEW YORK, N. Y., ASSIGNOR, BY MESNE ASSIGNMENTS,
TO ROYAL RAILWAY IMPROVEMENTS CORPORATION, OF NEW YORK, N. Y., A
CORPORATION OF DELAWARE.

REGULATOR FOR BRAKE RIGGING.

Application filed March 23, 1927. Serial No. 177,365.

This invention relates to improvements in regulators for the brake rigging of railroad cars and more particularly to manually operable regulators of the general type and character shown in my recently issued Patent, No. 1,612,581, dated December 28, 1926.

As fully explained in this patent, it is very important to have for the adjustment and regulation of the truck brake rigging a device or mechanism which will permit such adjustment or regulation in a minimum of time and to be absolutely foolproof in its construction and operation.

It is, therefore, with this primary object in mind that the present invention has been devised, as well as the production of a regulator which will be of simple and practical construction strong and durable to withstand hard usage, and reliable and efficient under all circumstances.

It is also an object of the present invention to provide a compact regulator of the above general character which may be easily and quickly installed on present railway equipment in a minimum amount of time and expense.

Other objects, such as the protection of various moving parts from the dust and dirt of the road, as well as atmospheric conditions will in part be obvious from the following analysis of the present invention and will in part be pointed out hereinafter.

Reference is accordingly made to the accompanying sheet of drawings wherein is shown one of the various possible embodiments of the present invention, and in its several views corresponding parts are similarly designated.

In these drawings—
40 Fig. 1 is an elevational view of such parts of the mechanism and associated car and brake rigging as is necessary to fully understand the same.

Fig. 2 is a vertical central sectional view showing the device in normal position.

Fig. 3 is a similar view showing the same parts in actuated position.

Fig. 4 is a vertical transverse section of the device.

Referring now to these drawings in detail, 5, for example, indicates the center draft sill of an ordinary freight car. This

draft sill is usually of structural iron, such as a flanged I-beam, and to one of the flanges of this beam there is rigidly secured as by means of rivets or bolts 6 a U-shaped hanger which preferably extends laterally in a horizontal plane with respect to the draft sill, altho obviously it could be suspended vertically therefrom or at an angle thereto as might be desired or necessary. This bracket or hanger is perhaps ten or twelve inches long, and the body portion is preferably of round stock steel, about an inch in diameter. Mounted upon this hanger is the regulator, which, in the preferred embodiment, comprises two drop forgings or steel plates, one mating with the other whereby when these plates 7 are secured together as by means of rivets or bolts 8 passing thru lugs 10 along the top and bottom edges of the plates, the two parts will embrace and enclose the body portion 11 of the hanger.

The lower parts of these plates are also provided with similar coacting semi-circular channels adapted to provide a cylindrical chamber thru which a regulating rod 12 is adapted to pass, and intermediate the upper and lower channels is formed a chamber 13 adapted to carry a pawl or detent 14 pivoted at 15 in holes in the side walls of the two plates 7. This pawl 14 normally engages one of a plurality of recesses, teeth or notches 16 in the normal upper surface of the regulator rod 12, and it will be noted that it is positively held in fixed engagement with said notches, inasmuch as its upper corner indicated at 17 bears against the under side of the body portion 11 of the supporting hanger. Therefore, as long as

these parts remain in normal position, and they will be held in such position by reason of the tension exerted upon the adjusting or regulating rod 12, there is absolutely no danger or even chance of the parts becoming disengaged. When the regulator is man-

ually actuated, however, as when adjusting the brake levers for proper brake shoe clearance, the adjusting rod 12 is moved relatively towards the left (Fig. 2 to Fig. 3) by grasping the depending weighted handle 18 and pulling upon the same which causes the adjusting rod 12 and the regulator to

move bodily towards the left until the pawl 14 is in such relative position with respect to the hanger as will permit its upper corner 17 to be forced upwardly under the action 5 of the teeth 16 into a releasing recess 20 in the under side of the body portion 11 of the hanger. Then any continued movement of the handle 18 towards the left will permit one or more of the teeth of the ratchet 10 16 to pass under the pawl 14, thereby permanently to take up and hold the excess travel of the brake rigging and restore the shoes to proper clearance. On release of the handle 18, the pawl 14 immediately drops 15 into the first tooth available, and the entire regulator is carried back or relatively towards the right (to Fig. 1) under the natural pull exerted by the brake rigging. It is, of course, to be understood that this regulator rod 12 is connected by means of a rod, 20 chain or other suitable connection 21 with a clevis 22 pivoted to the upper end of one of the brake levers 23 of the truck with which the device is associated.

25 As fully explained in my prior patent above referred to, it is highly desirable that both trucks and their associated parts be provided with proper brake shoe clearance in order that the brake shoes may go into effective position at the earliest possible moment upon application of the brakes either by hand or by air power. This brake shoe clearance for each truck is proportional to the 30 distance thru which the regulator is moved to bring the pawl 14 into coactive relation with the slot or recess 20, and, of course, varies with different types of trucks or sizes of cars. For this reason, there is preferably provided an adjustable clamp 24 on the body portion 35 40 11 of the hanger, thereby to limit the return of the regulator to its normal position of rest, as well as to determine the distance the regulator may move before the pawl reaches releasable position. Also, as in my prior 45 patent, means are, of course, provided and associated with the brake rigging of each truck at any convenient point whereby an adjustment or regulation movement of the 50 brake levers of one truck fail to have any effect whatsoever upon the other regulator or the angularity of the truck brake levers at the opposite end of the car.

The operation of this device is substantially as follows. Assuming the parts to be in the position shown in Fig. 2 and it is desired to test the accuracy or regulate the brake shoe clearance then existing, the operator first grasps the handle 18 of the adjusting rod and moves the same relatively towards the left as far as it will go with a normally hard pull. This motion is transmitted thru the adjusting rod 12, link or chain 21 to the upper end of the dead lever 23, which thereby brings the brake shoes into firm engagement with the peripheries of the wheels of that

particular truck. If the brakes are in properly adjusted position, then the pawl 14 merely moves to a position opposite the recess 20 whereby it may be forced up into this recess to release the ratchet on the lower rod. If the brakes are not in properly adjusted position, this position of the parts will permit the adjusting rod to be moved further, one or more teeth as may be necessary to absorb all of the excess brake shoe clearance. 75

The operator then releases the handle 18, and the pawl 14 drops into engaged position, (Fig. 3 to Fig. 2) and the entire regulator moves back relatively towards the right along the hanger 11, whereupon the operator is assured that the proper brake shoe clearance is instantly obtained. 80

It will be noted particularly that both the hanger 11 and adjusting rod 12 snugly fit in the recesses formed by the two abutting plates 7, and the pawl 14 is entirely enclosed within the housing or chamber 13 between these plates. Also, inasmuch as the plates are permanently riveted and secured together, there is no possibility of a workman, either intentionally or accidentally, reaching this pawl to move the same out of position, thus getting improper brake shoe clearance and abnormal piston travel with the resulting flat wheels, etc. Likewise the parts are fully protected from the dust and dirt of the road, as well as snow and ice, and are thereby free to be operated at any time. All that is necessary is for the inspector or operator to give one strong and full length pull upon the handle 18 and then release the same, whereupon he is assured that proper brake shoe clearance is established.

When it is necessary to put in new brake 105
shoes on the associated truck, it is, of course,
essential that the dead lever 23 be returned
to full release position. Under these cir-
cumstances, it is only necessary to pull out 110
upon the handle 18 until the pawl is opposite
recess 20 and then rotate the rod 12 thru 90°,
causing the pawl to ride up on the round
surface of this regulating rod, under which
circumstances it may be bodily moved rela-
tively towards the regulator casing to its full 115
release position. Such movement may move
the upper end of the dead lever 23 back
some six or eight inches, allowing ample
brake shoe clearance to permit the easy re-
moval of a worn shoe and the insertion of a 120
new brake shoe. When the brake shoes have
been inserted, the regulating or adjusting
movement above described is repeated there-
by to instantly bring the parts into proper
position with desired brake shoe clearance 125
and piston travel.

It is thus seen that the present invention comprises a simple and practical regulator for the brake rigging of railway cars which may be inexpensively manufactured and in- 139

stalled, and which primarily will be absolutely foolproof in its operation under all circumstances.

I claim—

5. 1. In a manually operated regulator for truck brake rigging, in combination, a support, a regulating rod in parallel position, and a regulator casing having a detent housed therein adapted to engage with said rod and be held in positive engagement therewith by said support, one of said parts having means permitting relative separation of the detent and rod during the regulating movement of the device.

15. 2. In a manually operated regulator for truck brake rigging, in combination, a support, a regulating rod in parallel position, and a regulator casing having a detent housed therein adapted to engage with said rod and be held in positive engagement therewith by said support, said support having a recess into which the detent is adapted to move, thereby to permit relative movement between the detent and rod during the regulating movement of the device.

3. In a manually operable regulator of the character described, in combination, a relatively fixed support upon which the regulator may be bodily moved, and a regulating rod, said regulator being provided with a recess embracing said support, and a second recess embracing said regulating rod, said rod and regulator being provided with coacting means normally held in fixed engagement when the parts are in normal operative position, said support having means permitting said parts to move temporarily out of operative holding relation when the rigging is being regulated, said parts thereafter resuming normal position permanently to hold excess travel.

4. In a manually operable regulator for truck brake rigging, in combination, a support for the regulator along which it may have relative movement, an adjusting rod connected with the truck brake rigging and provided with a ratchet along one side, a regulator casing closely embracing both the support and the adjusting rod, and having a chamber, a pawl mounted in said chamber cooperating with said ratchet and normally positively held against relative movement with respect to said ratchet while the parts are in normal position of rest, and means for moving the pawl and ratchet out of holding relation.

5. In a manually operable regulator for truck brake rigging, in combination, a support for the regulator along which it may have relative movement, an adjusting rod connected with the truck brake rigging and provided with a ratchet along one side, a regulator casing closely embracing both the support and the adjusting rod, and having a chamber, a pawl mounted in said

chamber cooperating with said ratchet and normally positively held against relative movement with respect to said ratchet while the parts are in normal position of rest, said support having a recess permitting relative movement of separation of the pawl and ratchet when the brake is being regulated.

6. In a manually operable regulator for truck brake rigging, in combination, a support for the regulator along which it may have relative movement, an adjusting rod having a ratchet along one side connected with the truck brake rigging casing closely embracing both the support and the adjusting rod, and having a chamber, a pawl mounted in said chamber cooperating with said ratchet and normally positively held against relative movement with respect to said ratchet while the parts are in normal position of rest, said support having a recess into which said pawl is adapted to move under the regulating movement of the device when proper or excess brake shoe clearance exists, and means whereby the pawl and ratchet may be thrown out of cooperative relation as and when it is desired to return the brake rigging to full release position.

7. In a manually operated regulator for brake rigging, in combination, a fixed support, a regulator casing movably mounted upon said support and having a housing therein, holding means completely enclosed in said housing, a regulating rod in parallel relation to said support passing thru said housing and having a coactive relation with said holding means, said support having means for permitting the holding means to move out of engagement with the regulating rod only when the regulator has been moved on said support to a position absorbing the entire brake shoe clearance.

8. In a manually operated regulator for truck brake rigging, in combination, a supporting rod, a regulating rod parallel thereto, a casing embracing said supporting rod, holding means completely housed within said casing and held in positive engagement with said second rod by said supporting rod, said rod having a recess into which said holding means may be moved after said regulator has been moved a distance proportional to brake shoe clearance, thereby to permit further movement of the regulating rod an amount proportional to excess brake shoe clearance.

9. In a manually operated regulator for brake rigging, in combination, a support, a regulating rod, a regulator casing embracing said support and rod, a pawl pivotally mounted and housed within said casing, a ratchet on said rod with which said pawl is held in constant engagement by said support, said support having a recess into which said pawl may be moved, said regulator having a free movement relative to said support.

proportional to brake shoe clearance at the end of which movement said pawl and ratchet may be moved relatively out of coactive relation whereby to permit further movement of the adjusting rod proportional to excess brake shoe clearance

10. In a manually operated regulator for brake rigging, in combination, a support, a regulating rod, a regulator casing embracing said support and rod, a pawl pivotally mounted and housed within said casing, a ratchet on said rod with which said pawl is held in constant engagement by said support, said support having a recess into which

said pawl may be moved, said regulator having a free movement relative to said support proportional to brake shoe clearance at the end of which movement said pawl and ratchet may be moved relatively out of coactive relation whereby to permit further movement of the adjusting rod proportional to excess brake shoe clearance, and means for throwing said pawl and ratchet out of coactive relation when it is desired to restore the parts to original full release position.

Signed at New York, New York, this 21st day of February, 1927.

W. H. SAUVAGE.
